UNITED STATES PATENT OFFICE

RILEY HERBERT PARKER, OF NORTH EASTHAM, MASSACHUSETTS, ASSIGNOR TO
GILLETTE SAFETY RAZOR COMPANY, OF BOSTON, MASSACHUSETTS, A CORPORATION
OF DELAWARE

SAFETY RAZOR

Application filed November 28, 1930. Serial No. 498,788.

This invention relates to safety razors and relates more particularly to a universal holder for safety razor blades.

An object of the invention is to provide a safety razor in which either a flexible blade or a rigid blade can be used.

There are two types of safety razors now generally employed. One type, known as the Gillette type, utilizes a transversely flexible blade having opposed longitudinal cutting edges, the blades being flexed between the cap and guard members of its holder to place the shaving edges in their proper position relative the guard. The other type of safety razor utilizes a non-flexible blade having only one shaving edge.

According to this invention, a safety razor is provided with which any of the commercial safety razor blades now available can be used. The possessor of a safety razor, according to this invention, is thus free from the necessity of keeping any particular make or type of blade in stock, all blades being equally usable.

In one embodiment of the invention, an ordinary type guard and handle is employed with a novel form of cap. The cap has its inner face adapted to flex a blade placed between it and the guard member, as is done in the ordinary Gillette type razor, and is provided also with a longitudinal aperture parallel and spaced behind one of its longitudinal sides through which the shaving edge of a non-flexible blade can be introduced, the blade being clamped upon the guard by the longitudinal edge portion of the cap.

The invention can be embodied in various forms, the preferred form herein described being one in which all of the parts of the holder are constructed as in the ordinary Gillette type razor with the exception of the cap piece, the latter being therefore capable of use in substitution for the cap piece of a Gillette type razor, constituting an article of manufacture.

A preferred embodiment of the invention will now be described with reference to the drawings, of which:

Fig. 1 is a side view of an assembled razor according to this invention;

Fig. 2 is a plan view looking down on the razor of Fig. 1;

Fig. 3 is a plan view of a cap piece of the safety razor shown by Figs. 1 and 2;

Fig. 4 is a side view showing a non-flexible blade inserted in the safety razor according to this invention;

Fig. 5 is a side view partially in section of the razor shown by Fig. 4, and

Fig. 6 is a partial view of the razor assembled with a flexible blade.

The safety razor illustrated comprises the guard piece 10, the lower portion 11 of which serves as a part of the handle of the razor. The guard 10 has the central aperture 12 which serves to receive the threaded stud 13 of the cap piece 14. The handle portion 11 of the guard 10 has the central aperture 15 which serves to receive the threaded portion 16 of the adjustable handle portion 17. The threaded portion 16 of the handle screws onto the threaded stud 13 of the cap piece 14 and upon rotation of the portion 17 of the handle, the cap piece 14 and the guard 10 are positioned together. The cap piece 14 is provided with the longitudinal aperture 18 extending parallel to and behind the longitudinal edge portion 19 of the cap piece. The longitudinal edge portion 19 is provided with the two extensions 20 which extend beyond the edge of and adjacent the ends of the longitudinal edge portion 19.

Figs. 1, 2, 3, 4 and 5 illustrate the safety razor of this invention utilizing a non-flexible blade. The cap 14 and the guard 10 are first assembled before the blade is inserted. Then before the cap piece 14 and the guard 10 are clamped tightly together, the non-flexible blade 21 is placed, as shown by Figs. 4 and 5, through the longitudinal aperture 18 in the cap piece 14. The blade 21 is passed through the aperture 18 until the edge portion 22 of the blade strikes against and is prevented from further movement by the extensions 20 of the cap piece 14. The cap piece 14 and the guard 10 are then clamped together by adjustment of the handle portion 17, the portion of the blade 21 just to the rear of the cutting edge 22 being clamped in position.

sition in contact with the guard 10 and the edge portion 19 of the cap piece 14.

The non-flexible blade 21 can be easily inserted and easily removed from the safety 5 razor and serves just as satisfactorily in this type of holder as in a holder designed solely for a non-flexible blade.

The holder illustrated may be used also with a transversely flexible razor blade, this 10 type of blade being shown clamped between the cap piece 14 and the guard 10 of the razor in Fig. 6 of the drawings. The flexible blade 23 is first assembled on the cap piece 14, the cap piece being provided with the 15 blade positioning studs 24 which fit in the positioning apertures (not shown) in the blade. The cap member 14 and the positioned blade are then assembled onto the guard 10. The blade is flexed into position by the clamping 20 action of the cap piece 14 and the guard 10 on tightening of the handle portion 17 (shown by Fig. 5). The one shaving edge 25 of the flexible blade 23 is contacted with by the guard 10 and the longitudinal edge 26 of the cap piece 14, this longitudinal edge 26 being similar to that used in the ordinary 25 type Gillette razors. The other shaving edge of the blade 23 is in contact with the edge portion 19 of the cap piece 14 which with a 30 flexible blade acts to flex the blade in exactly the same way as the normal edge 26 does. The edge portions 19 and 26 of the cap piece 14 are so arranged that they flex 35 their respective sides of a transversely flexible blade the same amount, the two edge portions 19 and 26 having the same length, being spaced the same distances from the center of the cap piece 14, and being arranged to position the shaving edges of the blade the 40 same, relative the guard 10 of the razor.

As before stated, the handle and guard portions of an ordinary Gillette type safety 45 razor can be employed with the novel form of cap piece described to enable both non-flexible and flexible blades to be utilized with easy facility in the one razor. When a non-flexible blade is used, the edge portion 26 of the cap piece 14 is not utilized, the razor in this instance having a single shaving edge. 50 When a transversely flexible two edged blade is used, both of the longitudinal portions of the cap piece are used, the two edges of the blade being equally available for shaving, except that small portions of one of the edges 55 of the flexible blade are guarded by means of the extensions 20.

Whereas one embodiment of the invention 60 has been described for the purpose of illustration, it should be understood that the invention is not limited to the exact details described as many departures may be made by those skilled in the art without departing from the spirit of the invention.

What is claimed is:

65 1. As an article of manufacture, a cap piece

for a safety razor, having means for securing it to the guard and handle portions of the razor, and adapted to serve as a clamping member for a blade placed between it and the guard portion, said cap piece being provided 70 with a slot arranged to permit the edge portion of a blade to be passed through it from above the cap piece.

2. As an article of manufacture, a cap piece for a safety razor, having means for 75 securing it to the guard and handle portions of the razor, and adapted to serve as a clamping member for a transversely flexible blade placed between it and the guard portion, said cap piece being provided with a 80 slot arranged to permit the edge portion of a non-flexible blade to be passed through it from above the cap piece.

3. As an article of manufacture, a cap piece for a safety razor, having means for 85 securing it to the guard and handle portions of a razor, and adapted to serve as a clamping member for a blade placed between it and the guard portion, said cap piece being provided with a slot arranged to permit the edge portion 90 of a blade to be passed through it from above the cap piece, and means for positioning the cutting edge of the latter blade in operative relation to the guard portion.

95 4. As an article of manufacture, a cap piece for a safety razor, having means for securing it to the guard and handle portions of the razor, and adapted to serve as a clamping member for a transversely flexible blade placed between it and the guard portion, said cap piece being provided with a slot arranged to permit the edge portion 100 of a non-flexible blade to be passed through it from above the cap piece, and means for 105 positioning the cutting edge of the latter blade in operative relation to the guard portion.

5. A universal type safety razor comprising 110 a guard, a cap piece shaped on its under side to flex a transversely flexible blade located between it and said guard, and being also provided with a slot through which the edge portion of a non-flexible blade can be passed from the upper side of said cap piece. 115

6. A universal type safety razor comprising 120 a guard, a cap piece shaped on its under side to flex a transversely flexible blade located between it and said guard, and being also provided with a slot through which the edge portion of a non-flexible blade can be passed from the upper side of said cap piece, and means forming a portion of said cap piece for positioning the cutting edge of the latter blade with respect to the guard. 125

7. A universal type safety razor comprising 130 a guard, a cap piece shaped on its under side to flex a transversely flexible blade located between it and said guard, and being also provided with a slot through which the

edge portion of a non-flexible blade can be passed from the upper side of said cap piece, means forming a portion of said cap piece for positioning the cutting edge of the latter blade with respect to the guard, and means for forcing said cap piece and said guard together.

Signed at North Eastham, Massachusetts,
this 21st day of November, 1930.

R. HERBERT PARKER.
